Attorney

UNITED STATES PATENT OFFICE

RALPH S. KELSO, OF ROCKFORD, ILLINOIS, ASSIGNOR TO FREE SEWING MACHINE COMPANY, OF ROCKFORD, ILLINOIS, A CORPORATION OF ILLINOIS

ATTACHMENT FOR SEWING MACHINES

Application filed November 21, 1929. Serial No. 408,856.

This invention relates to attachments for sewing machines, and more particularly to a light attachment for sewing machine heads to illuminate the bed of the machine.

5 An important object of the present invention is to provide a novel light supporting means for a sewing machine head which is readily adjustable to desired positions.

A further object is to provide friction means for supporting the light attachment whereby the attachment will be securely held in position and may be readily moved to adjusted positions.

10 A further object is to provide a novel connection between the light attachment and the head of a sewing machine whereby these elements in themselves provide pivot means for the light support, and provide means for securing the light support to the head of the 15 machine and to permit the turning movement of the support for adjusting purposes to take place.

Other objects and advantages of the invention will become apparent during the 20 course of the following description.

In the drawings I have shown one embodiment of the invention. In this showing,

Figure 1 is a side elevation of a sewing machine head showing the invention applied,

25 Figure 2 is a section on line 2—2 of Figure 1, and,

Figure 3 is a perspective view of the attachment.

Referring to the drawing, the numeral 10 30 designates a sewing machine head including a horizontal arm 11. The wheel 12 of the machine is illustrated as being adapted to be driven by a suitable motor 13. The elements referred to constitute a generally standard 35 sewing machine construction and form no part of the present invention.

The horizontal arm 11 of the machine is provided at the rear side thereof with an 40 integral boss 14 having a circular bearing recess 15 formed therein as shown in Figures 1 and 2. The numeral 16 designates an attaching element including a hollow cylindrical outer portion 17 and an inner substantially circular plate 18 corresponding in size 45 to and adapted to be arranged in the circu-

lar recess 15. The plate 18 is provided preferably at diametrically opposite points with concentric arcuate cut away portions or slots 19, for a purpose to be described.

50 A pair of screws 20 is threaded in the arm 11 and pass through the cut away portions 19 of the plate 18. Each screw is provided with a head 21 which engages against the outer face of the boss 14 and frictionally engages against the outer face of the plate 18 to 55 resist revolving movement thereof in the recess 15. The plate 18 is approximately equal in thickness to the depth of the recess 15, but the heads of the screws are adapted to engage 60 more tightly against the outer face of the boss 14 than against the face of the plate 18. Accordingly the screws may be driven in 65 tightly to maintain them in position, and the heads of the screws will frictionally engage the outer face of the plate 18 as stated.

70 A tubular member 22 is connected between the cylindrical member 17 and a light socket 23, as shown in Figures 1 and 3. The member 17 is provided with an opening 24 through which a suitable electric cable 25 extends and 75 this cable also extends through the tubular member 22 for connection with the proper elements of the socket 23. A pull chain 26 or any other suitable means is provided for the socket 23 for turning the latter on or off as 80 desired. An elongated tubular electric light bulb 27 is mounted in the socket and is surrounded by a suitable reflecting shield 28 connected at its upper end to the socket by means 85 of a screw 29.

The operation of the device is as follows: 90 The plate 18 is of the same diameter as the socket 15, and accordingly the latter acts as a bearing for the plate to permit the latter to swing about the axis of the cylindrical member 17. The screws 20 serve the double function of securing the plate 18 in position against accidental dislodgement and also as frictional means for retaining the light support in adjusted positions. Accordingly 95 when it is desired to move the light upwardly it merely is necessary to swing the light support against the friction of the heads of the screws, and the light support will remain in any desired adjusted position, as for example, 100

the dotted line position illustrated in Figure 1.

When it is desired to return the light to normal position, this readily may be done merely by pushing downwardly on the support, as will be apparent. It also will be apparent that the light may be directed as desired by revolving the reflector 28 about the axis of the socket 23, and accordingly light at any desired point may be secured. The flexible cable 25 obviously permits adjustment of the light support in the manner referred to.

The device does not require the placing of any parts within the sewing machine head, and it will be apparent that the device readily may be attached or detached by inserting or removing the screws 20.

It is to be understood that the form of the invention herewith shown and described is to be taken as the preferred example of the same and that various changes in the shape, size and arrangement of parts may be resorted to without departing from the spirit of the invention or the scope of the subjoined claims.

I claim:

1. The combination with a sewing machine head having a shallow circular recess therein, of a light support including a circular plate at one end thereof corresponding in shape and size to said recess and rotatably mounted therein, said plate being provided with arcuate cut away portions concentric therewith, and screws passing through said cut away portions and secured in the head of the machine, the heads of said screws engaging said plate to frictionally resist turning movement thereof.

2. The combination with a sewing machine head having a shallow circular recess therein, of a light support including a circular plate at one end thereof corresponding in shape and size to said recess and rotatably mounted therein, said plate being provided with arcuate cut away portions concentric therewith, and screws passing through said cut away portions and secured in the head of the machine, said screws being provided with heads adapted to tightly engage against the metal of the head of the machine surrounding said recess and to frictionally engage said plate to resist turning movement thereof.

3. A device of the character described comprising an arm, means for supporting a light at one end of said arm, a circular plate carried by the opposite end of said arm parallel thereto and offset therefrom and adapted to be arranged in a recess in a supporting structure, and means for securing said plate in said recess and for frictionally engaging said plate to resist turning movement thereof in said recess.

4. A device of the character described comprising an arm, means for supporting a light

at one end of said arm, a circular plate carried by the opposite end of said arm parallel thereto and offset therefrom and adapted to be arranged in a recess in a supporting structure, said plate being provided with arcuate concentric cut away portions, and screws for securing said plate in said recess and extending through said cut away portion, said screws being provided with heads adapted to frictionally engage said plate to resist turning movement thereof.

In testimony whereof I affix my signature.

RALPH S. KELSO.
